CLAIM

The ornamental design for an adjustable archery bow sight as shown and described.

DESCRIPTION

FIG. 1 is a front perspective view of an adjustable archery bow sight;

FIG. 2 is a back perspective view of an adjustable archery bow sight;

FIG. 3 is a side elevational view of an adjustable archery bow sight;

FIG. 4 is a side elevational view of an adjustable archery bow sight;

FIG. 5 is a front elevational view of an adjustable archery bow sight;

FIG. 6 is a back elevational view of an adjustable archery bow sight;

FIG. 7 is a top elevational view of an adjustable archery bow sight; and,

FIG. 8 is a bottom elevational view of an adjustable archery bow sight.

The broken lines shown in the figures depict portions of the adjustable archery bow sight that form no part of the claimed design.
